UNITED STATES PATENT OFFICE

2,025,550

ELECTRIC CONNECTER

Robert F. Sambleson, Bridgeport, Conn., assignor
to General Electric Company, a corporation of
New York

Application May 19, 1934, Serial No. 726,545

3 Claims. (Cl. 173—332)

My invention relates to electric connectors and more particularly to detachable plug connectors such as are used on electric toasters, flat irons and other electric appliances.

Heretofore, difficulty has been encountered in the use of electric connectors of the type above referred to because of poorly made electrical connections inside the connector member which have resulted in short circuits with consequent injury to the connector. Much of this difficulty has come about because of carelessness in attempting to repair the device and improperly reassembling it. Hence, it is an object of my invention to provide an improved electric connector which cannot be tampered with after it has been connected to an electric cord.

A further object of my invention is to provide an improved electric connector which will be more rugged and durable.

Another object of my invention is to provide an electric connector of the type indicated which may be easily and economically manufactured.

What I consider to be novel and my invention will be better understood by reference to the following specification and appended claims when considered in connection with the accompanying drawing in which Fig. 1 is a perspective view of an electric connector embodying my invention; Fig. 2 is a plan view with the insulating casing shown in section; Fig. 3 is an exploded view of the connector shown in Figs. 1 and 2; and Fig. 4 is a perspective view of the terminal assembly prior to its insertion in the body member.

Referring to the drawing, 10 indicates a body member of insulating material. As best shown in Fig. 2 the member 10 is a unitary block having a large chamber 11 open at one end and communicating with a smaller opening 12 at the other end. Insulating members 13 and 14 are mounted in face engagement in the chamber 11. The walls of the chamber 11 may be provided with grooves as shown in Fig. 1 to receive the members 13 and 14 and prevent lateral movement thereof. Insulating member 13 and 14 are provided with lateral projections 15 and 16 respectively. I prefer to provide these lateral projections with upstanding lugs 17 which engage the holes 18 in terminal contacts 19. When the terminal assembly is completed as shown in Fig. 4 the terminal contacts 19 are held between the lateral projections 15 and 16 of insulating members 13 and 14 respectively. In order to prevent lateral movement of the terminal contacts,

projections 20 may be provided on the terminal contacts which engage shoulders 21 on the insulating members.

Terminal contacts 19 are connected to wires 22 and 23 of conductor cord 24. The conductor cord 24 is preferably provided with a strain reliever 25 which may be formed of rubber or other flexible insulating material molded directly around the end of the cord, the wires 22 and 23 projecting beyond it. Thus the strain reliever is, in substance, an integral part of the cord. The strain reliever 25 surrounds a portion of the conductor cord 24 adjacent its end and extends beyond the point at which it leaves the opening 12 of body member 10 thus preventing fraying of the insulating covering of the cord through friction with the body member. The strain reliever 25 is provided with an enlargement 26 which is so shaped as to fit snugly against the interior wall of chamber 11 adjacent opening 12. Enlargement 26 is also provided with an indentation 27 into which the ends of insulating members 13 and 14 fit in order to hold the strain reliever 25 firmly in place.

A U-shaped spring 28 with laterally projecting ends 29 is carried by the insulating members 13 and 14. These insulating members are provided with registering grooves 30 adjacent holes 31. The spring 28 is placed in the registering grooves 30 with the ends 29 projecting through holes 31. Notches 32 are provided in the opposite walls of chamber 11 extending from opening 12 and forming shoulders 33 for engagement with the ends 29 of spring 28.

In assembling the connector member described above the terminal contacts 19 are attached to wires 22 and 23 of cord 24. Spring 28 is placed between insulating members 13 and 14 in the grooves 30 with its ends 29 projecting through holes 31. The terminal contacts 19 are clamped between projections 15 and 16 of insulating members 13 and 14. The assembly is completely while the end of cord 24 extends from the large opening of chamber 11. The cord 24 is then pulled back through the chamber 11, and the entire terminal assembly slipped into the body member 10, spring member 28 being compressed by engagement with the walls of chamber 11. When the terminal assembly reaches its proper position the ends of spring 28 snap into notches 32 in engagement with shoulders 33 in the interior chamber 11 so that the terminal assembly is firmly locked in place. The terminal contacts 19 are firmly clamped in place by the insulating members 13 and 14 which are mounted

in the body member 10 as described above. The insulating members 13 and 14 when in their final position press firmly against notch 27 in enlargement 26 so that it is held rigidly in place, all possible strain on the connections being obviated. When the connector is thus assembled it cannot be again disassembled without destroying the body member 10 since the locking means, namely spring 28, is entirely enclosed within the body member. It will thus be seen that I have provided an electric connector which is relatively easy to manufacture and assemble, in which the parts are adequately protected from strain and injury and which when assembled form a complete non-tamperable unit.

15 While I have described my invention as embodied in concrete form in accordance with the patent statutes, it should be understood that I do not limit my invention thereto since various 20 modifications thereof will suggest themselves to those skilled in the art without departing from the spirit of my invention, the scope of which is set forth in the annexed claims.

25 What I claim as new and desire to secure by Letters Patent of the United States, is:

1. An electric connector comprising a body member of insulating material having an opening in one end thereof for the insertion of a conductor cord, a pair of insulating members mounted 30 in said body member, a plurality of terminal contacts clamped between said pair of insulating members, and a compressible spring member

carried by said pair of insulating members and adapted to engage opposite interior walls of said body member.

2. An electric connector comprising a body member of insulating material having an opening in one end thereof for the insertion of a conductor cord, a pair of insulating members secured in face engagement in the center of said body member and dividing the latter into a plurality of parallel recesses, a terminal contact 10 mounted in each of said recesses and lateral projections on said pair of insulating members adapted to clamp said terminal members therebetween.

3. An electric connector comprising a body member of insulating material having an opening in one end thereof for the insertion of a conductor cord, a pair of insulating members mounted in face engagement in the center of said body member and dividing the latter into a plurality of 20 parallel recesses, a terminal contact mounted in each of said recesses, lateral projections on said pair of insulating members adapted to clamp said terminal members therebetween, notches on opposite interior walls of said body member, 25 spring means provided with outwardly projecting ends carried by said pair of insulating members, said outwardly projecting ends engaging shoulders formed by said notches to hold said pair of insulating members in place. 30

ROBERT F. SAMBLESON.
